UNITED STATES PATENT OFFICE

BRUNO BAUER, OF VIENNA, AUSTRIA

REINFORCED CONCRETE BRIDGE

Application filed September 22, 1927, Serial No. 221,267, and in Austria July 23, 1927.

Heretofore reenforced concrete bridges of a medium span only could enter into economical competition with iron bridges. In the case of larger spans, the costs of building reinforced concrete bridges were excessively increased in consequence of the increased weight and the necessity of erecting in the river, sea or water a scaffold carrying the shells.

10 This invention relates to a method of building or erecting reenforced concrete bridges, according to which not only the dead weight of the arches of the bridge is reduced considerably, but also the erection of expensive scaffolds and shells is rendered unnecessary. This object is attained in that the standardized bridge-arches are divided into sections which, during the erection, form independent units and render possible the erection of the bridge 15 in such a manner, that owing to the manufacture of the individual parts of the arch one after the other, the carrying capacity of the bridge is increased gradually. The method according to the present invention is carried 20 out for instance in such a manner, that a light bridging is at first built which consists of a light iron-structure, the halves of which are mounted on the two shores and which are subsequently folded together about a hinge 25 and which does not require a larger carrying capacity than would correspond to the dead weight of the unnecessary cast iron cores for a part of the arch together with the weight 30 of the workmen and their tools.

25 In the event of larger spans, an arch of this kind can be made also of individual members by means of the so-called American erecting methods. If a light bridging has been made in this way, completely finished arch-cores of braced cast iron are put together in 35 individual arches, which after the fitting together are connected with one another, whereby their carrying capacity increases in accordance with the increasing erection of such 40 individual arches.

45 In all known similar bridge-constructions, arch-supports consisting of a heavy riveted iron-construction were employed, which subsequently were also imbedded in concrete, while according to the present invention

members consisting of braced cast-iron are used.

Several modes of carrying out the present invention are illustrated by way of example on the accompanying sheets of drawings, in which—

Fig. 1 shows in side view a braced cylindric cast iron core provided with downwardly directed straps for attaching the shell.

Fig. 2 illustrates in cross-section the cast iron core shown in Fig. 1, and

Fig. 3 is the side view of a sleeve-shaped connecting wedge.

Fig. 4 shows in side view a modified construction of a cast iron core, which is enlarged in one direction, and

Fig. 5 illustrates in cross-section the substantially rectangular shaped core shown in Fig. 4.

Figs. 6 and 7 illustrate, in side view and cross-section respectively, members used as curved cores.

Fig. 8 shows in elevation and cross-section respectively connecting wedges used in connection with the cores shown in Figs. 6 and 7.

Figs. 9 and 10 illustrate in cross-section reenforced concrete bridges according to the present invention.

Fig. 11 is a plan view of a fragment of a reenforced concrete bridge.

In Figs. 1 and 2, *d* designates the downwardly directed straps of the core for the attachment of the shell.

In Figs. 6 and 7 each member, used as a curved core, consists of two separate braced cast iron cores *e* and *f*, which are retained and connected with one another in properly spaced end to end relation by means of rods *g* and wedges or rings *h* or in any other convenient manner.

In the construction shown in Fig. 9 curved cores are employed according to Figs. 6, 7 and 8, while in the construction illustrated in Fig. 10 the cores are constructed according to Figs. 4 and 5.

In the case of arched bridges, braced cast iron and the usual round iron protection and, as in the case of other concrete bridges, shell-scaffolds had to be employed, while according to the present invention the braced cast iron

members can be encased in sheet iron shells, which are supplied in conjunction with the cast iron and permit concreting. The cast iron members may be provided with extensions for guiding the shells, so that the finished bridge is in the shape of a reenforced concrete member containing braced cast iron and compared with a solid concrete arch is comparatively light in weight, as an iron reinforcement is imbedded in the usual manner.

I claim—

In reenforced concrete bridge construction, a core for the concrete, said core comprising an independent supporting arch acting as such and consisting of a plurality of pre-formed metallic pressure resistant rods, each wrapped in bracing wire and means for retaining said plurality of rods together in properly spaced end to end relation.

In testimony whereof I affix my signature.

DR. BRUNO BAUER.
